UNITED STATES PATENT OFFICE

ANDRÉS SANTALLA FONSECA, OF HABANA, CUBA

TOBACCO CLEANING MACHINE

Application filed May 10, 1930. Serial No. 451,355.

This invention is directed to an improvement in tobacco cleaning machines, and particularly to a machine wherein the leaf is subjected to a thorough brushing or cleaning action on each of the respective surfaces thereof whereby to positively remove the dust, eggs, larva, small grubs and other surface impurities.

The primary object of the present invention is the provision of a machine in which the leaves are handled in succession and automatically presented first with one surface to the influence of brushing or cleaning elements and then the other surface to a similar cleaning action of successive brushing elements, the respective surfaces of the leaves being automatically and successively exposed for cleaning in the movement of the leaf through the machine.

A further object of the invention is the provision of cylindrical carriers on which the leaves are successively presented for cleaning operation, there being combined with each of the carriers a particular type of pneumatic means whereby the leaf is held on the carrier for the brushing operation, the disposition of the carriers and of the pneumatic means combined therewith being such that in the transfer of the leaf from the initial carrier to the succeeding carrier, the leaf is reversed with respect to its exposed surface, whereby one surface may be cleaned on one carrier and the opposite surface on the succeeding carrier.

A further object of the present invention is the provision of pneumatic means in the form of suction to hold the leaves on the respective carriers throughout a predetermined length of travel, provision being made for projecting the leaf at will to a greater suction effect during the immediate cleaning operation than in preceding or following such cleaning operation, thereby insuring that the leaf may be properly held on the carrier during the actual cleaning operation to prevent relative movement of the leaf in the action of the cleaners.

The invention is illustrated in the accompanying drawings, wherein:—

Figure 1 is a view in side elevation of the improved machine.

Figure 2 is a plan of the same.

Figure 3 is a section on the line 3—3 of Fig. 1.

Figure 4 is a vertical sectional view through the respective carriers on the line 4—4 of Fig. 2.

Figure 5 is a vertical section through one of the carriers, the line of section being at 60 right angles to that of Fig. 4.

Figure 6 is a broken vertical section of one of the carriers with the vacuum box in place.

Figure 7 is a perspective view of the 65 vacuum box.

Figure 8 is a perspective view of one of the carriers partly broken out.

The machine of the present invention involves an appropriate skeleton framework, 70 the various bars, braces and connecting parts of which are indicated generally by the reference numeral 1, it being understood that the frame structure is arranged for the convenient mounting of the various parts of the machine and may be constructed of any appropriate material and in any relative arrangements so long as the machine parts are properly accommodated and supported.

In order that the operation of the various parts may be properly understood as the description proceeds, it is deemed advisable to first describe the operating mechanism for the various parts. This operating mechanism includes a motor 2, energization of which is 80 controlled through a switch 3, which motor is mounted in the lower portion of the frame. In substantially the same horizontal plane of the motor and mounted on appropriate bars of the frame is a shaft 4 driven from the motor by a belt 5. A shaft 6 intermediate the motor and shaft 4 is driven from shaft 4 by a belt 7, there being provided on the shaft 6 for the reception of the belt 7 fast and loose pulleys 8 and 9, a convenient belt shifter 10 providing for the proper control of the shaft 6 from the shaft 4. A shaft 11 is mounted beyond the shaft 4 relative to the motor and on the shafts 6 and 11 are arranged relatively 90 reverse cone pulleys 12 and 13 respectively, 95 100

the connecting belt 14 of which is arranged to be shifted by a shifting element 15 having threaded connection with a rod 16 mounted in the frame and controlled by a handle 17. Obviously, through shifting of the belt 14, the relative speeds of the shafts 6 and 11 may be controlled.

The shaft 18 is mounted in the frame beyond the shaft 11 and driven from the latter through the medium of a belt 19. On shaft 11 equally spaced on opposite sides of its center are belt pulleys 20, from which extend belts 21 for operating one of the carriers, as will later appear. A belt pulley 22 is also arranged on the shaft 18 for operating the tobacco feeding belt, as will later appear. A shaft 23 is arranged immediately beyond the shaft 18 with intermeshing gears 24 connecting the shafts to insure their absolutely uniform predetermined movement.

Pulleys 25 are arranged on the shaft 23, from which extend belts 26 for operating the other carrier, the shaft 23 being also provided with a pulley 27 for operating the tobacco feeding belt and a pulley 28 by which the lower cleaning element or brush will be operated, as will later appear.

On the frame above the plane of the operating mechanism described and in alignment longitudinally of the machine is arranged the respective carriers 29 and 30. These carriers are identical in construction, differing only in the relative position of the suction box, and a detailed description of one such carrier will suffice for both, it being understood that the reference characters of one carrier will be duplicated on the other. Each carrier includes two circular heads 31 and 32, preferably in the form of wooden disks. These heads are arranged in spaced parallel relation and their peripheral edges are connected by a transverse plate-like section 33 of metal, which section is formed with a series of perforations 34 throughout its full area.

The disks 31 and 32 are formed at their center with an opening for the passage of a hollow bearing shaft 35 on which the disks rotate, reinforcing metal gaskets 36 and 37 being secured on opposite faces of each disk to reinforce the opening, the gasket 36 being preferably inserted in the disk on the inner surface thereof and the gasket 37 overlying the outer surface of the disk and provided with rotating arms 38 to be secured to the disk for reinforcing the mounting.

Annular strips 39 of a diameter materially less than that of the carrier project from the outer surface of each disk 31 and 32 concentric with the carrier, the outer edges of the strips having cover plates 40 formed with central openings to rotatably embrace the shaft 35. The strips 39 constitute pulleys, one on each side of the carrier, whereby the latter may be driven. In the case of the carrier 29, these pulleys 39 are connected with

the pulleys 20 on shaft 18 by belts 21, while in the case of the carrier 30 the pulleys 39 thereon are connected with the pulleys 25 on shaft 23 by belts 26.

Thus each carrier is driven by a belt on each side thereof and the operation is balanced and exactly synchronized. The hollow shafts 35 are mounted in bearing blocks 41 on appropriate parts of the framing 1 so that, as illustrated in Figure 1, the peripheral surfaces of the respective carriers 29 and 30 are substantially in contact at one point. Of course, incident to the gear connections 34 between the shafts 18 and 23, it will be apparent that the carriers 29 and 30 will be rotated in opposite directions, this being arranged so that their surfaces which are substantially in contact move downwardly, as indicated by the arrows in Figure 1.

As stated, the carriers and operating pulleys therefor rotate on the hollow shaft 35 in each instance and such shaft is provided with fixed, annular abutments 42 for maintaining the rotating position of the carrier on the shaft and preventing relative endwise movement of the parts.

A suction box 43 is arranged in each carrier, these suction boxes being identical. Each suction box comprises spaced walls 44 and 45 connected by end plates 46 and 47. The side walls 44 and 45 and the inner ends of the end plates 46 and 47 bear on and are fixed to the hollow shaft 35 and within the area of the shaft included between the ends of the end walls 46 and 47 and for a length corresponding to the distance between the side walls 44 and 45, the peripheral wall of the hollow shaft 35 is formed with an opening 48.

As will be plain from Figures 4 and 6, the suction box occupies a space within the carrier which is materially less than half the area of the carrier, and the side walls 44 and 45 of the suction box are in comparatively close association, just avoiding contact with the disks 31 and 32 of the carrier. Arranged within each suction box and fitting the space between the side walls 44 and 45 are parallel walls 49 and 50, these walls being spaced apart a distance approximating the similar dimension of the opening 48 in the hollow shaft 35 and extending from the peripheral edges of the walls 44 and 45 to a point somewhat short of the hollow shaft 35, as indicated clearly in Figures 4 and 6. The radial length of the suction box corresponds to that of the carrier so that the free edges of the walls 44 and 45 of the suction box rest in close proximity to the peripheral plate 33 of the carrier.

The various walls 40, 46, 49, 50 and 47 define free suction chambers 51, 52 and 53, the chamber 51 being between the walls 46 and 49, the chamber 52 being between the walls 49 and 50, and the chamber 53 being between the walls 50 and 47. The inner surface of

the walls 49 and 50 are provided with gates 54 and 55 connected by a rod 56 branched at the upper end to permit it to be secured to both gates, and a lever 57 extending longitudinally through one end of the hollow shaft 35, that end of the shaft being closed except for a slot 58 to permit the passage of the lever 57, and such lever being provided with a plate 59 to maintain the slot closed against air admission in any position of the lever. The lever 57 is pivoted on a pin 60 arranged transverse the hollow shaft 35, and it will be apparent that by operation of the lever the gates may be moved toward or from the opening 48, thereby accentuating or reducing the suction in the chamber 52 at will.

The gates 54 and 55 may, if desired, have pin and slot connection with the walls 59 and 50, as indicated at 61 in Figure 5, thereby limiting the movement of the gates in both directions. It will be understood that when the gates are in their lowered position, as indicated in Figure 6, the chamber 52 is subjected to a greater suction than when the gates 25 are in the elevated position indicated in Figure 4, it being understood, however, that the suction is at no time or in any position of the gates cut off from the chambers 51 and 53.

As will appear from Figure 4 of the drawings, the respective carriers 29 and 30 have a point of substantial peripheral contact at 62, the proximate surfaces of the carriers moving in the same direction, that is, downwardly. The suction boxes of the respective carriers are oppositely arranged; in that the final wall 46 of the suction box in carrier 29 is on a plane slightly above the initial wall 46 of the suction box in carrier 30 so that there 35 is a suction effect on the leaf resting on the peripheral plate 34 of carrier 29 retained on at least a portion of that leaf until the suction effect of the suction box in the carrier 30 begins to act on the leaf.

A cleaning brush 63 is mounted above the carrier 29 in alignment with the chamber 52 of the suction box in that carrier, a similar brush or cleaning element 64 being mounted below the carrier 30 in line with the chamber 50 52 of the suction box therein. These brushes or other appropriate cleaning elements are mounted on shafts 65 and 66 respectively supported in the framework 1, the shaft 65 being driven from a pulley 67 on shaft 4, while the 55 shaft 66 is driven from pulley 28 on shaft 23. The tobacco leaves are delivered to the carrier 29 on a delivery belt 68 operating over pulleys 69 and 70, the pulley 69 being arranged adjacent the periphery of the carrier 60 practically in line with the wall 47 of the suction box therein. The belt 68 is operated by a belt 71 driven from the pulley 22 on shaft 18 so that the tobacco leaves are delivered onto the carrier 29 at the initial edge 65 of the suction chamber 53.

In order that the leaves may be properly and evenly presented to the cleaning brush, there is arranged between the end of the delivery belt 68 and such brush a shaft 72 having a plurality of rollers 73 thereon with intervening spacing blocks 74, the roller shaft 72 being supported in brackets 75 influenced by springs 76 to maintain the rollers in contact with the perforated plate 33 of the carrier. The spacing blocks 74 are provided with fingers 77 which overlie and rest upon the surface of the carrier, terminating immediately adjacent the juncture of the brush with the carrier surface.

Immediately beyond the brush, a pressure roll 78 is supported in brackets 79 connected with the framing 1 and, influenced by spring 80, is arranged to exert a pressure on the tobacco leaf to insure its physical contact with the plate 35 and prevent a tendency for the brush to displace the leaf. A similar pressure roll 81 influenced by spring 82 is arranged to bear on the surface of the carrier 30 in advance of the brush 64, and beyond the brush 64 is arranged the tobacco discharge belt 83 operated by belt 84 from pulley 27 on shaft 23.

The respective hollow shafts 35 of the carriers 29 and 30 are connected at the ends remote from the levers 57 with branches 85 leading from a trunk 86 connected to a source of suction (not shown). The branches 85 have a non-leaking fit in the ends of the hollow shaft 35 so that the chambers 51, 52 and 53 of each suction box are under continuous suction in the operation of the apparatus.

With the parts arranged as described, the tobacco leaves to be cleaned are fed in succession by means of the belt 68 to the surface of the carrier 29. During the travel of these leaves on the particular portion of the carrier, they are held to the peripheral surface of such carrier by the suction in the successive chambers 53, 52 and 51. During this operation they are subjected to the action of the brush 63 and the uppermost or exposed surface of the leaf is thoroughly cleaned of all extraneous matter. As the carrier continues its rotation, the leaf is carried around on the surface thereof, finally and before passing completely beyond the influence of the suction box in the carrier 29, being forced against the surface of the carrier 30 and picked up by the suction of the suction box in such carrier.

Of course, in its movement on the carrier 30, the surface of the leaf which was next the plate 33 on the carrier 29 is now exposed or outermost with respect to the carrier 30, so that the brush 64 which cooperates with the carrier 30 is now operating upon the surface of the leaf opposite that which was operated on by the brush 63. Thus both surfaces of the leaf are thoroughly cleaned, the respective surfaces being presented to the re-

spective brushes automatically and in a simple, expeditious manner. The various feeding instrumentalities serve to hold the leaf to the carriers and present it smoothly and evenly to the action of the brush. The leaf is finally delivered onto the delivery belt 83 and carried away from the machine.

If at any time as, for example, with leaves requiring an unusually heavy brushing action, or for any other purpose it is found necessary to secure the leaf on the particular carrier under increased suction during the brushing action, the levers 57, or either of them, may be operated to lower or move inwardly the gates 54 and 55, with the effect to reduce the suction opening to the chambers 51 and 53 and thereby increasing the suction effect in the chamber 52.

As these chambers are in direct line with the brushes of the respective carriers, it will be apparent that while the brush is actually operating on the leaf, the leaf is under the maximum suction, thus insuring that the leaf cannot be casually displaced from the carriers.

25 I claim:—

1. A tobacco cleaning machine including successive tobacco leaf carriers, cleaning means cooperating with the leaf on each carrier, means operating to hold the leaf on each carrier throughout a predetermined movement of the carrier, the leaf on successive carriers exposing relatively opposite faces.

2. A tobacco cleaning machine including successive carriers, leaf cleaning means cooperating with each carrier, and suction means in the carrier for holding the leaf thereon throughout a predetermined movement of the carrier, the cooperation of the carriers and the relation of the suction means in each carrier serving to transfer the leaf from one carrier to the other.

3. A tobacco cleaning machine including successive rotating carriers, having a point of substantial peripheral contact leaf cleaning means cooperating with each carrier, and suction means in the carrier for holding the leaf thereon throughout a predetermined movement of the carrier, the cooperation of the carriers and the relation of the suction means in each carrier serving to transfer the leaf from one carrier to the other, the leaf in cooperation with the respective carriers presenting relatively opposite surfaces for cleaning.

4. A tobacco cleaning machine including successive carriers, and cleaning means cooperating with each carrier, fixed suction means in each carrier, the position of the suction means in each carrier and the relation of the carriers causing the suction means of a successive carrier to pick up the leaf from a preceding carrier to expose a surface of that leaf opposite the surface exposed on such preceding carrier.

5. A tobacco cleaning machine including rotating carriers moving in opposite directions and in immediately adjacent relation, a leaf cleaning means cooperating with each carrier, and suction means arranged in each carrier and held against movement, the suction means of the respective carriers causing the leaf from one carrier to be transferred to the other carrier in a relatively reverse position.

6. A tobacco cleaner including a plurality of cylindrical carriers arranged in successive order, the relative adjacent surfaces of the carriers moving in the same direction and substantially in contact, a suction device in one carrier serving to hold the leaf on the carrier, a suction device in the other carrier serving to hold the leaf on such other carrier, the suction devices in the respective carriers being so relatively disposed that the suction effect on the leaf on the first carrier is released substantially coincident with the initial suction effect on the leaf on the second carrier, and a cleaning means cooperating with each carrier.

7. A tobacco leaf cleaner including two successive carriers of cylindrical form, means for operating the carriers to cause their proximate peripheral surfaces to move in the same direction and substantially in contact, a suction box in each carrier held against movement with the carrier, the suction box of the second carrier being arranged to affect the tobacco leaf when the latter has passed beyond the influence of the suction box of the first carrier, each of the suction boxes including a manually controllable suction chamber, and a cleaning element cooperating with the peripheral surface of each carrier and arranged in radial alignment with said chamber.

8. A tobacco leaf cleaner including two carriers arranged in successive order so that the surface of one is substantially in contact with the surface of the other, means for operating the carriers in relatively opposite directions to cause their contacting surfaces to move in the same direction, each carrier including a peripheral surface to receive and support a tobacco leaf with such surface perforated, a suction box fixed within and held against movement with respect to the first carrier, a second suction box fixed within and held against movement with respect to the second carrier, the suction effect of such boxes being transmitted to the leaf through the perforated peripheral surfaces of the carriers whereby to hold the leaf in contact with such surface, the suction effect of the box of the first carrier terminating immediately in advance of the initial suction effect of the box of the second carrier whereby the leaf held to the first carrier by its suction box is transferred and held to the peripheral surface of the second carrier

through the suction box of the latter, and tobacco leaf cleaning means cooperating with each carrier.

9. A tobacco leaf cleaner including two carriers arranged in successive order so that the surface of one is substantially in contact with the surface of the other, means for operating the carriers in relatively opposite directions to cause their contacting surfaces to move in the same direction, each carrier including a peripheral surface to receive and support a tobacco leaf with such surface perforated, a suction box fixed within and held against movement with respect to the first carrier, a second suction box fixed within and held against movement with respect to the second carrier, the suction effect of such boxes being transmitted to the leaf through the perforated peripheral surfaces of the carriers whereby to hold the leaf in contact with such surface, the suction effect of the box of the first carrier terminating immediately in advance of the initial suction effect of the box of the second carrier whereby the leaf held to the first carrier by its suction box is transferred and held to the peripheral surface of the second carrier through the suction box of the latter, and a tobacco leaf cleaning brush cooperating with each carrier within the effective area of the suction box within that carrier.

10. A tobacco leaf cleaner including two carriers arranged in successive order so that the surface of one is substantially in contact with the surface of the other, means for operating the carriers in relatively opposite directions to cause their contacting surfaces to move in the same direction, each carrier including a peripheral surface to receive and support a tobacco leaf with such surface perforated, a suction box fixed within and held against movement with respect to the first carrier, a second suction box fixed within and held against movement with respect to the second carrier, the suction effect of such boxes being transmitted to the leaf through the perforated peripheral surfaces of the carriers whereby to hold the leaf in contact with such surface, the suction effect of the box of the first carrier terminating immediately in advance of the initial suction effect of the box of the second carrier whereby the leaf held to the first carrier by its suction box is transferred and held to the peripheral surface of the second carrier through the suction box of the latter, each suction box including a suction chamber, means for manually controlling the suction effect on the carrier in line with the chamber, and a tobacco leaf cleaning means cooperating with each carrier.

11. A tobacco leaf cleaner including two carriers arranged in successive order so that the surface of one is substantially in contact with the surface of the other, means for operating the carriers in relatively opposite direc-

tions to cause their contacting surfaces to move in the same direction, each carrier including a peripheral surface to receive and support a tobacco leaf with such surface perforated, a suction box fixed within and held against movement with respect to the first carrier, a second suction box fixed within and held against movement with respect to the second carrier, the suction effect of such boxes being transmitted to the leaf through the perforated peripheral surfaces of the carriers whereby to hold the leaf in contact with such surface, the suction effect of the box of the first carrier terminating immediately in advance of the initial suction effect of the box of the second carrier whereby the leaf held to the first carrier by its suction box is transferred and held to the peripheral surface of the second carrier through the suction box of the latter, each suction box including a suction chamber, means for manually controlling the suction effect on the carrier in line with the chamber, and a cleaning brush cooperating with the peripheral surface of each carrier in line with such chamber of each suction box.

12. In a tobacco cleaning machine, a cylindrical carrier having a perforated peripheral surface, a fixed hollow shaft on which said carrier is mounted for rotation, a suction box secured to the shaft and extending within the carrier, the walls of the box providing a suction area opening through the coincident portion of the peripheral surface of the carrier, a source of suction connected with the hollow shaft, said hollow shaft being formed with an opening communicating with the suction box, and a tobacco leaf cleaning means cooperating with the surface of the carrier.

13. In a tobacco cleaning machine, a cylindrical carrier having a perforated peripheral surface, a fixed hollow shaft on which said carrier is mounted for rotation, a suction box secured to the shaft and extending within the carrier, the walls of the box providing a suction area opening through the coincident portion of the peripheral surface of the carrier, a source of suction connected with the hollow shaft, said hollow shaft being formed with an opening communicating with the suction box, said suction box including spaced parallel walls defining a suction chamber, gates whereby the suction effect in said chamber may be controlled, and a tobacco leaf cleaning means cooperating with the carrier.

14. In a tobacco cleaning machine, a cylindrical carrier having a perforated peripheral surface, a fixed hollow shaft on which said carrier is mounted for rotation, a suction box secured to the shaft and extending within the carrier, the walls of the box providing a suction area opening through the coincident portion of the peripheral surface of the carrier, a source of suction connected with the hollow shaft, said hollow shaft being formed

with an opening communicating with the suction box, said suction box including spaced parallel walls defining a suction chamber, gates whereby the suction effect in said chamber may be controlled, means for manually operating the gates, and a tobacco leaf cleaner means cooperating with the carrier.

15. In a tobacco cleaning machine, a cylindrical carrier having a perforated peripheral surface, a fixed hollow shaft on which said carrier is mounted for rotation, a suction box secured to the shaft and extending within the carrier, the walls of the box providing a suction area opening through the coincident portion of the peripheral surface of the carrier, a source of suction connected with the hollow shaft, said hollow shaft being formed with an opening communicating with the suction box, said suction box including spaced parallel walls defining a suction chamber, gates whereby the suction effect in said chamber may be controlled, means for manually operating the gates, and a cleaning brush cooperating with the peripheral surface of the carrier in line with said chamber.

In testimony whereof I affix my signature.

ANDRÉS SANTALLA FONSECA.
